HOUSED DRAFT GEAR

Emil H. Blattner, Williamsville, N.Y., assignor to The Symington Wayne Corporation, a corporation of Maryland

Application November 10, 1955, Serial No. 546,033

10 Claims. (Cl. 213—40)

This invention relates generally to draft gears for railway vehicles and more particularly to draft gears of the housed type.

The primary object of the invention is to provide an improved draft gear of the housed type wherein a plunger at at least one end of the housing by which longitudinal forces are transferred to one end of the cushioning mechanism, is insertible in the housing through an opening in a side thereof, thereby enabling a relatively simple and rugged construction of both plunger and housing effectively to limit the relative outward movement of the plunger.

Another object of the invention is to provide an improved draft gear of the type described wherein the plunger, at at least one end of the housing, acts directly on a rubber cushion and both plunger and cushion are insertible through an open side of the housing.

An additional object of the invention is to provide an improved housed draft gear having a plunger at either end and employing a plurality of rubber cushions, the several components being so constructed and arranged as to provide a draft gear combining high capacity with relatively long travel and consequent softness of action under buffing forces.

A further object of the invention is to provide an improved selective travel draft gear of the housed type employing rubber cushions and plungers at either end for relatively long travel under buffing forces.

Another object of the invention is to provide an improved housed draft gear of the double-ended type wherein resilient and friction means are utilized to yieldably resist and cushion longitudinal forces and the resiliency is supplied entirely by rubber cushions.

Other objects and advantages of the invention will appear hereinafter in the detailed description, be particularly pointed out in the appended claims and be illustrated in the accompanying drawings, in which

Figure 1 is a side elevational view of one embodiment of the draft gear of the present invention with portions broken away and shown in section to more clearly illustrate certain of the details of construction;

Figure 2 is a plan view of the draft gear of Figure 1 with portions broken away and shown in section to more clearly illustrate certain of the details of construction;

Figure 3 is an end elevational view taken from the rear end of the draft gear of Figure 1;

Figure 4 is a vertical sectional view taken along the lines 4—4 of Figure 2;

Figure 5 is a view partly in elevation and partly in vertical section taken along the lines 5—5 of Figure 2;

Figure 6 is a side elevational view of another embodiment of the draft gear of the present invention with portions broken away and shown in section to more clearly illustrate certain of the details of construction;

Figure 7 is a plan view of the draft gear of Figure 6 with portions broken away and shown in section to more clearly illustrate certain of the details of construction;

Figure 8 is a vertical sectional view taken along the line 8—8 of Figure 7;

Figure 9 is a vertical sectional view taken along the lines 9—9 of Figure 7; and

Figure 10 is an end elevational view taken from one end of the draft gear of Figure 6.

Referring now in detail to the drawings in which like reference characters designate like parts, both of the illustrated embodiments of the draft gear of the present invention are of the double-ended type in which longitudinal forces are transmitted to the cushioning mechanism within the housing through a plunger seated in either end. In both, at least one end of the housing houses a rubber cushion and is open-sided for enabling the rubber cushion and the associated plunger to be inserted into their respective seats through the opening in the side of the housing, this construction, as will be explained, affording a draft gear of simple and rugged construction. Although each utilizes rubber as its sole resilient means, the embodiments differ in several respects and will now be described separately.

Referring first to the embodiment of Figures 1—5, the draft gear of this embodiment employs both friction and resilient means for snubbing longitudinal forces, the friction means being in the form of a plurality of transversely or laterally spaced counterpart shoes or wedges 1 seated in a housing 2 and having wedging faces 3 frictionally engaging corresponding wedging surfaces 4 formed on opposite walls 5 of the housing 2 within and adjacent an open end 6 thereof. The friction surfaces 4 on the opposite side walls flare or diverge outwardly relative to each other towards the end of the housing and the shoes 1, when in position, are limited in their outward movement relative to the housing by the lateral overlap between outstanding feet 7 forming the inner ends of the shoes and instanding shoulders 8 demarking the inner ends of the friction surfaces 4.

The shoes are urged apart and into frictional engagement with the housing by leaf spring or other resilient means, a rubber cushioning unit being preferred and that illustrated being of the "Waugh-Mat" type which is made up of alternating rubber pads 10 and metal plates 11 with the pads joined in pairs through the intervening plates. The shoes 1 and interposed rubber cushions 9 thus are adapted to both yieldably or resiliently and frictionally resist any forces applied at that end of the draft gear through a plunger 12 seated in the adjacent open end or mouth 6 of the housing and having rubbing engagement with the outer ends of the shoes. The plunger, when seated, is pressable inwardly but restricted in outward movement relative to the housing, so as to hold this portion of the draft gear's cushioning mechanism in assembled relation, by suitable means such as the disclosed pins 13.

55 The part of the housing 2 in which the shoes and associated cushioning unit are contained is closed at all four sides. However, the remainder of the housing, to a point adjacent its opposite end, is open-sided to provide a pocket 14 open completely or unrestrictedly over a pair of its opposite sides and closed on its other pair of sides by opposite, substantially parallel longitudinal extensions 15 of the walls 5 of the housing on which the friction surfaces 4 are formed. Both to reinforce these walls and to seat an associated second plunger 16, the walls over the end portion 17 of the housing opposite that seating the shoes 1 are connected at either side by webs 18 disposed substantially parallel to each other and coplanar with the corresponding 19 of the pairs of opposed walls enclosing the shoes 1. 60 Within the pocket between the inner transverse wall 20 of the second plunger 16 and the opposed face 21 of a floating follower 22, the opposite face of which rubs

against the inner ends of the shoes 1, is a rubber cushion 23 similar in composition to but of greater capacity than the first rubber cushioning unit 9 and acting longitudinally of the housing instead of laterally, as does the first unit.

Conventionally, a plunger is inserted into a housing through the open end of the latter, as is the first described plunger 12, necessitating either that the plunger be canted during application or that it be held in place by means drivable inwardly to overlap the plunger laterally, as are the pins 13. By contrast, the plunger 16 at this end of the housing, while having a body or main portion 24 of substantially box shape which extends through and projects from the longitudinally extending passage or mouth 25 of the housing defined by the extensions 15 of the walls 5 and the connecting webs 18, has a pair of integral flanges 26 outstanding from opposite sides and substantially coterminous in outward extent with the corresponding outside lateral or transverse dimension of the housing. The inner wall or base 20 of the plunger 16 thus is substantially equal in cross section to the pocket 14, while the body 24 of the plunger and the passage 25 in which it slides are both relatively restricted. It is desirable for strength to thicken the flanges 26 towards their inner extremities with their outer or rear faces 27 tapering or converging rearwardly and to correspondingly bevel the confronting edges of the webs 18 to provide a seat 28 for seating the plunger in the normal position of the latter.

With the above construction the plunger is enabled to be slid or inserted into its seat 28 from within the housing 2 through either of the open sides 29 of the pocket 14 without canting and, when seated, is limited in outward movement relative to the housing by the engagement of the flanges 26 of its extended base 20 with the seat 28. It will, of course, be understood that in assembly the second rubber cushion 23 which, along with the first cushion 9, preferably is precompressed or under initial compression to eliminate slack in the mechanism and is insertible through one of the open sides 29 of the housing, is inserted in the pocket 14 after the plunger has been seated.

In Figures 6-10 the present invention is shown embodied in a double-ended draft gear of the selective travel type. The illustrated draft gear of the second embodiment is comprised of a housing 30 having an open-sided pocket 31 towards either end, similar in construction to the pocket 14 of the first embodiment, for receiving and seating one of the two longitudinally acting rubber cushions 32, the latter preferably being of the type known as "Waugh-Mats," previously described. Each of the pockets 31 is closed at its inner end by one of a pair of longitudinally spaced, transverse intermediate walls 33 in the housing. The pockets are unrestricted or open on a pair of their opposite sides and enclosed on their other two sides by a pair of transversely spaced, substantially parallel longitudinal walls 34, here the side walls, which extend the length of the housing. At the outer or opposite ends of the pockets 31 and relatively restricted in cross-section, are the longitudinally opening opposite passages, mouths or openings 35 in the housing, each of which is defined by the side walls 34 and a pair of transversely spaced webs 36 connecting the side walls adjacent their outer extremities or corners. As in the case of that in the rearward portion of the first embodiment, the passage 35 at each end of the draft gear of this embodiment is adapted to slidably receive the body portion 37 of a plunger 38 which has a base 39 substantially co-extensive in cross section with the associated pocket 31 and, in the direction of the integral flanges 40 at either side of the base, is substantially coterminous with the corresponding outside transverse dimension of the housing 30. So, also, the flanges are thickened at their inner extremities and their outer faces 41 converge or taper outwardly and are adapted to seat

against and be restricted in outward movement relative to the housing by correspondingly inclined or beveled surfaces 42 on the webs 36. With this construction, the plungers 38 are enabled to be inserted into their seats through either open side of the associated of the pockets 31 and on subsequent insertion into each pocket of one of the rubber cushions 32, each is adapted to be pressed, forced or pushed inwardly against the resistance of the precompressed rubber cushion and on release of this force, to return to its seat.

The total travel in the present standard A.A.R. draft gears is $2\frac{1}{2}$ inches. Both embodiments of the draft gear of the present invention are designed to provide greater travel on the order of $4\frac{1}{2}$ inches with corresponding increase in capacity and to fit between the center sills (not shown) of a railway car in an oversize draft gear pocket such as is now under contemplation by the A.A.R. The draft gear of the first embodiment has the same maximum travel under both buffing and draft forces. However, that of the second embodiment is of the selective travel type, affording full travel under buffing forces and more limited travel under the lesser draft forces.

To the above end, the housing 30 between the intermediate walls 33 has a column or post 43 extending transversely of the housing, here horizontally, this central portion of the housing being reinforced at either side by spaced longitudinally extending ribs 44 connected to both the intermediate walls and the column. The column 43 is open through its center to provide a key slot 45 for the reception of the usual draft key (not shown), the draft key in turn extending beyond the key slot through aligned, rearwardly elongated slots (not shown) in the center sills (not shown). If, as in the usual application, the draft gear is contained vertically by the jaws (not shown) of a vertical yoke (not shown), the rearward elongation of the slots in the center sills will permit both rubber cushions 32 to be compressed by their plungers 38 between conventional front and rear follower blocks 46 under buffing forces but block or lock out the forward of the cushioning units under draft forces, the slots in the center sills then acting as pulling stops.

The draft gear of the first embodiment not being designed to have a key connection to the center sills, both of its plungers 12 and 16 can be forced inwardly when one or the other of the conventional follower blocks 46 reacts against the associated stop lugs (not shown) on the center sills (not shown) and the pair of cushioning mechanisms within the housing will act in series to resist compressive forces, depending only on the amount of force applied and regardless of whether this force is a buffing or a draft force.

From the above detailed description, it will be apparent that there has been provided an improved draft gear of the housed type in which at least one rubber cushion is contained in an open-sided pocket and compressed under longitudinal forces by an associated plunger, the construction and arrangement of the several components being such as to simplify their construction, facilitate assembly and render the draft gear efficient and rugged in operation, and that in the illustrated embodiments there have been provided double-ended draft gears of high capacity and long travel in at least one direction. It should be understood that the described and disclosed embodiments are merely exemplary of the invention and that all modifications are intended to be included which do not depart from either the spirit of the invention or the scope of the appended claims.

Having described the invention, what is claimed is:

1. A draft gear comprising a housing, a pocket in said housing, a side opening to said pocket in a side of said housing, means closing an inner end of said pocket, a passage restricted in cross section relative to said pocket and extending therefrom through an adjacent end of said housing, a unitary plunger seated in said passage and in-

sertible thereinto through said side opening in said housing, said plunger having a portion inwardly of and of greater cross-sectional area than said passage for limiting outward movement of said plunger relative to said housing, and a rubber cushion seated in said pocket between said closed end and said plunger and insertible thereinto through said side opening for yieldably resisting inward movement of said plunger relative to said housing.

2. A draft gear comprising a housing, a unitary plunger at each end of said housing and pressable inwardly relative thereto against yieldable resistance under longitudinal forces, a pocket toward at least one end of said housing and opening unrestrictedly through a pair of opposite sides thereof, means closing an inner end of said pocket, a passage of less cross section than said pocket and opening therefrom through an adjacent end of said housing, one of said plungers seating in said passage and being insertible thereinto from within said housing through an open side of said pocket, said plunger inwardly thereof being of greater cross-section than said passage for limiting outward movement of said plunger relative to said housing, and a rubber cushion seated in said pocket between said closed end and said plunger and insertible thereinto through an open side of said pocket for yieldably resisting inward movement of said plunger relative to said housing.

3. A draft gear comprising a housing, a unitary plunger at each end of said housing and pressable inwardly relative thereto under longitudinal forces, a plurality of rubber cushioning means in said housing and each yieldably resisting inward movement of one of said plungers, a pocket adjacent to one end of said housing and opening unrestrictedly through opposite sides thereof, means closing an inner end of said pocket, and a passage of less cross-section than and extending from said pocket through said one end of said housing, one of said plungers seating in said passage and being insertible thereinto through an open side of said housing, said one plunger inwardly of said passage having a base portion greater in cross-section than said passage and substantially equal in cross-section to said pocket for limiting outward movement of said plunger relative to said housing, and one of said rubber cushioning means being insertible into said pocket through a side thereof and yieldably resisting inward movement of said one plunger.

4. A draft gear comprising a housing, a pair of longitudinally spaced pockets in and each adjacent an opposite end of said housing and each opening unrestrictedly through a pair of opposite sides thereof, means in said housing closing inner ends of and spacing said pockets, a passage of less cross-section than and opening from each of said pockets through an adjacent end of said housing, a unitary plunger seating in each of said passages and insertible thereinto through an open side of the associated of said pockets, each of said plungers inwardly of its respective passage having a portion of greater cross-section than said passage and engageable with means on said housing for limiting outward movement of said plunger relative thereto, and a rubber cushion seating in each of said pockets and insertible thereinto through an open side thereof for yieldably resisting inward movement of the associated of said plungers under longitudinal forces.

5. A draft gear comprising a housing, a pair of longitudinally spaced pockets in and each adjacent an opposite end of said housing and each opening unrestrictedly through a pair of opposite sides thereof, longitudinally spaced transverse walls in said housing and each closing an inner end of one of said pockets, a passage of less cross-section than and opening from each of said pockets through an adjacent end of said housing, a unitary plunger seating in each of said passages and insertible thereinto through an open side of the associated of said pockets, each of said plungers inwardly of its respective

passage having a portion of greater cross-section than said passage and engageable with means on said housing for limiting outward movement of said plunger relative thereto, a rubber cushion seating in each of said pockets and insertible thereinto through an open side thereof for yieldably resisting inward movement of the associated of said plungers under longitudinal forces, and a key slot extending transversely through said housing intermediate said transverse walls and cooperating through a draft key with aligned slots in center sills for blocking out one of said cushioning means on application of longitudinal forces from one direction to said draft gear.

10 6. A draft gear comprising a housing, a plunger at each end of said housing and pressable inwardly thereof under longitudinal forces, friction means in and frictionally engaging said housing, resilient means in said housing and urging said friction means transversely into said frictional engagement, said friction and resilient means coacting to yieldably resist inward movement of one of said plungers, a pocket in said housing between an opposite end thereof and said friction means, a side opening to said pocket in a side of said housing, a passage of less cross-section than and opening from said pocket through said opposite end of said housing, the other of said plungers seating in said passage and being insertible thereinto through said side opening to said pocket, said other plunger inwardly of said passage having a base portion of greater cross-section than said passage for limiting outward movement of said plunger relative to said housing, and rubber cushioning means seating in said pocket between said other plunger and said friction means for yieldably resisting inward movement of said other plunger.

15 7. A draft gear comprising a housing, a plunger at each end of said housing and pressable inwardly thereof under longitudinal forces, a pair of counterpart friction shoes within and adjacent one end of said housing and each having a friction face engaging a corresponding friction surface on said housing, resilient means between and urging said shoes transversely and said faces and surfaces into frictional engagement, said friction shoes and resilient means coacting to yieldably resist inward movement of one of said plungers, a pocket in said housing between an opposite end thereof and said friction means, said pocket extending unrestrictedly through a pair of opposite sides of said housing, a passage of less cross-section than and opening from said pocket through said opposite end of said housing, the other of said plungers seating in said passage and being insertible thereinto through an open side of said pocket, said other plunger inwardly of said passage having a base portion of greater cross-section than said passage for limiting outward movement of said plunger relative to said housing, and rubber cushioning means seating in said pocket between said other plunger and said friction means for yieldably resisting inward movement of both of said plungers.

20 8. A draft gear comprising a housing, a plunger at each end of said housing and pressable inwardly thereof under longitudinal forces, a pair of counterpart friction shoes within and adjacent one end of said housing and each having a friction face engaging a corresponding friction surface on said housing, a rubber cushion between and urging said shoes transversely and said faces and surfaces into frictional engagement, said friction shoes and rubber cushion coacting to yieldably resist inward movement of one of said plungers, a pocket in said housing between an opposite end thereof and said friction means, said pocket extending unrestrictedly through a pair of opposite sides of said housing, a passage of less cross-section than and opening from said pocket through said opposite end of said housing, the other of said plungers seating in said passage and being insertible thereinto through an open side of said pocket, said other plunger inwardly of said passage having a

each end of said housing and pressable inwardly thereof under longitudinal forces, a pair of counterpart friction shoes within and adjacent one end of said housing and each having a friction face engaging a corresponding friction surface on said housing, resilient means between and urging said shoes transversely and said faces and surfaces into frictional engagement, said friction shoes and resilient means coacting to yieldably resist inward movement of one of said plungers, a pocket in said housing between an opposite end thereof and said friction means, said pocket extending unrestrictedly through a pair of opposite sides of said housing, a passage of less cross-section than and opening from said pocket through said opposite end of said housing, the other of said plungers seating in said passage and being insertible thereto through an open side of said pocket, said other plunger inwardly of said passage having a base portion of greater cross-section than said passage for limiting outward movement of said plunger relative to said housing, and rubber cushioning means seating in said pocket between said other plunger and said friction means for yieldably resisting inward movement of both of said plungers.

base portion of greater cross-section than said passage for limiting outward movement of said plunger relative to said housing, rubber cushioning means seating in said pocket inwardly of said other plunger and insertible thereto through an open side thereof, and a floating follower between said last named rubber cushion and said friction shoes, said last-named rubber cushion yieldably resisting inward movement of both of said plungers relative to said housing.

9. A draft gear comprising a housing, a plunger at each end of said housing and pressable inwardly thereof under longitudinal forces, friction means in and frictionally engaging said housing, resilient means in said housing and urging said friction means transversely into said frictional engagement, said friction and resilient means coacting to yieldably resist inward movement of one of said plungers, a pocket in said housing between an opposite end thereof and said friction means, a side opening to said pocket in a side of said housing, a passage of less cross-section than and opening from said pocket through said opposite end of said housing, the other of said plungers seating in said passage and being insertible thereto through said side opening to said pocket, said other plunger inwardly of said passage having a base portion of greater cross-section than said passage for limiting outward movement of said plunger relative to said housing, and rubber cushioning means seating in said pocket between said other plunger and said friction means for yieldably resisting inward movement of both of said plungers.

10. A draft gear comprising a housing, a plunger at
